Patented Nov. 26, 1963

196,996

COVERED WAGON GRILL

Richard Kates, Park Lane, Madison, N.J.

Filed Apr. 25, 1963, Ser. No. 74,667

Term of patent 7 years

(Cl. D81—10)

I claim:

The ornamental design for a covered wagon grill, as shown.
